FIG. 1 is a side elevational view of a carpet unloading and transporting apparatus embodying our new design; FIG. 2 is a top plan view thereof; FIG. 3 is an end elevational view thereof; and FIG. 4 is a perspective view thereof.

The broken lines shown in FIGS. 1, 2 and 3 are for illustrative purposes only.

The opposite side to that shown in FIG. 1 is essentially a mirror image of FIG. 1.

We claim:

The ornamental design for a carpet unloading and transporting apparatus, as shown and described.
